ONE-PIECE STUD AND SOCKET

Daniel I. Reiter, New York, N. Y.

Application November 22, 1933, Serial No. 699,716

13 Claims. (Cl. 24—216)

This invention relates to one-piece snap fasteners and snap fastener installations and particularly, to the type disclosed in my co-pending application for patent for One-piece stud and socket, Serial No. 680,969. In my said co-pending application, I have shown a one-piece snap fastener element in the form of a socket made from a flat blank, which blank is provided with radiating arms, the arms being bent to form the sides 5 of the socket and part of the tubular wall thereof and the ends of the alternate arms being bent outwardly to form a discontinuous flange, the ends of the remaining arms being bent to form 10 resilient fingers.

In my said co-pending application, I have further shown a one-piece snap fastener element in the form of a stud formed similarly to the socket from a flat blank having radiating arms, and provided with portions adapted to be bent 15 to form a flange provided with interlocking segments, the end portions of said arms being bent outwardly to form a discontinuous flange similar to that of the socket element.

It will be understood that in both the socket 20 and stud blanks, the end portions of the arms are first drawn up into tubular form. When sold, the lower part of the fastener remains in the form of a tube, the user performing the flanging operation by bending the lower parts of the arms 25 outwardly when the element is to be secured to a sheet of material.

In order to give the surfaces of the fasteners a proper finish, said fasteners are tumbled in a suitable machine such as a ball tumbling machine. During the tumbling operation, or when the fasteners are fed from a hopper to a setting machine, the unbraced or weaker parts of the element are likely to become distorted or bent 30 as by the action thereon of the tumbling balls. Furthermore, the arms of the discontinuous flange formed from the lower part of the fastener element, when applied to flexible material such as leather, fabric or the like, are likely to pull out through the opening of the sheet of 35 material under stress applied to the element.

My present invention therefore contemplates the provision of a self-reinforcing tubular part on the element which is not likely to become bent or distorted during the tumbling operation 40 or when tumbled in or fed from a hopper or otherwise abnormally but moderately stressed.

My invention further contemplates the provision of flange-forming means on the lower part of the element, which when bent outwardly to 45 form the securing flange thereof, firmly grips the

sheet of material around an area in the shape of an annular ring and thereby forms a secure attaching flange not likely to be pulled out through the hole in the sheet through which the tubular portion of the element is inserted.

My invention further contemplates the provision of an attaching flange which is practically complete and thereby presents a finished appearance.

My invention further contemplates the provision of an inexpensive and efficient snap fastener installation providing a one-piece resilient socket and a one-piece stud adapted to be firmly secured to comparatively flexible sheet material such as leather, fabric or the like though it will be understood that the installation may be used in connection with comparatively rigid material such as card-board, wood or the like, if desired.

The various objects of my invention will be clear from the description which follows, and from the drawing, in which,

Fig. 1 is a vertical section of a snap fastener installation embodying my invention.

Fig. 2 is a similar section of the socket element as it appears after it has been inserted through a hole in the sheet but before the flanging operation has been performed.

Fig. 3 is a similar section of a modified form of the socket element in which the resilient fingers are bent downwardly and outwardly instead of upwardly and inwardly.

Fig. 4 is a bottom plan view of the socket element shown in Fig. 2.

Fig. 5 is an elevational view of a blank from which the sockets of Figs. 2 and 3 may be made.

Fig. 6 is a vertical section of one form of the stud element embodying my invention.

Fig. 7 is a top plan view of the same.

Fig. 8 is a bottom plan view of the same.

Fig. 9 is a fragmentary elevational view of a blank from which the stud element may be made.

Fig. 10 is an elevational view partly in vertical section of a modified form of the stud element wherein the stud head and sides are unslotted, but the lower thickness of the material of the flange is formed of separate members and interlocked.

Fig. 11 is a top plan view of the stud shown in Fig. 10.

Fig. 12 is a fragmentary bottom plan view of the same.

In the practical embodiment of my invention which I have shown by way of example, and referring particularly to Fig. 1, the one-piece

socket element 10 operatively engages the one-piece stud element 11.

The socket is secured to a sheet of material 12, which while preferably of flexible material, may instead if desired, be comparatively hard or stiff material such as wood, card-board or the like. The stud 11 is secured to a similar sheet 13, the socket being provided with suitable resilient fingers adapted for snapping engagement and disengagement with the stud.

The socket 10 is preferably made from a suitable flat blank as 14 (Fig. 5). The central portion 15 of the blank is imperforate and is adapted to be stamped, drawn or otherwise operated upon to form the imperforate dome-shaped cap or visible portion 16 of the socket. The sides of the socket are formed from the innermost parts 17 of the separate arms radiating from the central portion 15, the edges of such arms being brought into adjacent relation. On alternate arms are provided the portions 18 (between the dash-dot lines 19 and 20) forming alternate sections of the uppermost parts 21 of the tubular portion of the socket. Said tubular portion is continuous and integral with the socket sides 17 and depends therefrom. On each of the remaining alternate arms, a somewhat longer portion 22 corresponding to the portions 18 forms the other part of the tubular portion 21.

The terminal portions 23 of the arms are bent upwardly and inwardly as in Fig. 2 to form the resilient fingers 24 or are bent downwardly and outwardly as in Fig. 3 to form the resilient fingers 25, the fingers in either case being adapted to engage the neck of the stud 11 and to yield during the passage of the head of the stud therepast. The alternate arms, beyond the dash-dot line 20, terminate in circular segments as 26, designed to be bent outwardly from the tube-forming position thereof shown in Fig. 2, to form the attaching flange for the socket.

Said segments 26 are of sufficient width on the outer and inner peripheral edges to form a substantially complete or closed flange best illustrated in Fig. 4.

It will be understood that the blank 14 is first drawn up into the shape of Fig. 2 wherein the imperforate portion 15 is shaped to form the head or cap of the socket. The parts 17 of the separate arms form the sides of said cap, the remainder of the arms being shaped and arranged to form the tube or tubular portion 21. Since, however, the widths of the portions 26 are comparatively great and are larger than their respective proportionate parts of the tubular wall (in the case illustrated, one-quarter), at least the divergent edge portions 27 of said segments 26 overlap each other, as is best seen in Fig. 2. The overlapping operation may be performed in any suitable manner, as by first bending alternate segment-carrying arms into their tube-forming positions, and then bending the remaining segment-carrying arms to a position outwardly thereof. Nevertheless, the tubular portion 21 is made of substantially the diameter of the hole or opening 28 in the sheet 12 so that said tubular portion may be passed through the hole 28 preparatory to flanging over the segments 26 on to the under surface 29 of said sheet. In other words, the greatest width of the segment 26 is greater than the circumference of the tubular wall 21 divided by the number of flange-forming arms. During the flanging operation, during which the segments 26 are bent outwardly, said segments are spread apart from their overlapping

positions and assume the positions shown in Fig. 4, wherein at least part of said segments 26 are in contact and form a substantially complete flange.

It will be understood that by making the edges 30 of the segments 26 more nearly radial of the blank, said edges may be brought closer to each other in the bent positions thereof as is, for example, shown in connection with the stud blank of Fig. 9 and which will be later described in more detail, in which case the width at 20 may be increased to the desired extent.

Referring now to Figs. 6 to 9 inclusive, I have there shown a resilient one-piece stud formed from the flat blank 31 of Fig. 9. Said blank is provided with an imperforate central portion 32 from which is drawn the imperforate top forming the extreme upper part of the stud head. The sides and neck of the stud are formed from the innermost parts 33 of the arms 34, said parts 33 being suitably bent for that purpose into edge-adjacent relation, and being constricted at their lower ends to form the neck 35 of the stud. The next outermost portions 36 of the arms 34 form the uppermost thickness of the doubled flange 47. Said portions 36 are provided with interlocking 25 and corresponding projections and recesses. As shown, the projection 37 is made on one of the edges of the portion 36, and the corresponding recess 38 is made on the other edge. It will be understood, however, as pointed out in my said co-pending application, that the projections and recesses may be otherwise arranged so as to interlock with each other. The next adjacent portions 39, arranged outwardly of the portions 36, form the under thickness of the flange 47. The outermost portions 40 of the arms 34 form the lowermost tubular portion of the stud and are similar to the segments 26 hereinbefore described in connection with the socket. The edges 41 of the portions 40 are so arranged that when the portions 40 are turned on to the under face 42 of the sheet of material 13, said edges 41 are in contact or substantially in contact as shown in Fig. 8.

As has been hereinbefore indicated, the side edges 30 of the segments 26 of the socket may similarly be arranged at the desired angle to bring them in contact when flanged over.

It will be seen that the tubular portion of the stud is similar to the tubular portion 21 of the socket, the separate members which are combined to make up said tubular portion overlapping to some extent due to their shape, since the outermost edges thereof are longer than the innermost edges, as is best shown in Figs. 6 and 9.

In that form of my invention shown in Figs. 10 to 12 inclusive, the head 50 of the stud, the neck 51 and the uppermost thickness 52 of the doubled flange 53 are unslit, imperforate and continuous, the central portion of the blank being imperforate for that purpose, or of a continuous piece as distinguished from separate arms in a manner which will now be obvious. The interlocking projections 54 and recesses 55 are here formed on the under thickness of the flange 53 instead of the upper thickness thereof, as has been hereinbefore described in connection with Fig. 6. By making the head and the upper thickness of the stud imperforate, said stud becomes more resistant to the distorting action of use, of the tumbling operation and of the operations necessitated in feeding the studs into setting position in a suitable setting machine.

It will be noted that the sheet of material, in the case of the socket, is clamped between the sides 17 and the flange formed by the segments 26

to secure the socket to the sheet. Similarly, in the case of the stud, the sheet 13 is clamped between the flange 47 and the flange formed by the segments 40 to firmly secure the stud to the sheet.

5. It will be seen that I have provided a one-piece fastener installation, and snap fastener elements each adapted to be made economically from a single flat blank, that said elements are self-reinforced against distortion during the finishing 10 and setting operations thereon, and are adapted to be flanged to form a substantially complete annular ring not likely to tear out through the hole in comparatively soft material through which they may be inserted, and presenting a finished appearance when attached in place.

While I have shown and described certain specific embodiments of my invention, it will be understood that I do not intend to limit myself thereto, but that my intention is to claim my invention as broadly as is permitted by the scope of the appended claims and the state of the prior art.

I claim:

1. In a one-piece snap fastener element having a part adapted to engage one face of a sheet of material, a tubular portion depending from and of less diameter than said part, said tubular portion comprising a series of separate members each of least width at the point adjacent said part and of greatest width at the extreme end thereof remote from said point, the end portions of said members overlapping the end portions of the adjacent members and being adapted to be bent outwardly against the other face of the sheet and in sufficiently close relation to each other to form a substantially complete annular flange securing the element to the sheet.

2. In a one-piece snap fastener element comprising an operating portion and an attaching portion, said attaching portion comprising a plurality of separate members arranged in overlapping relation to form a tube-like part adapted to pass through an opening in a sheet of material to which the element is to be secured, said members being adapted, when bent outwardly against the face of the sheet and out of their overlapping relation to form an annular attaching flange for the element and being of sufficient width for that purpose and said members mutually bracing and reinforcing each other and thereby preventing distortion of said tube-like part during a tumbling or setting operation on said element.

3. A one-piece snap fastener element comprising an operative portion adapted to engage a cooperating snap fastener element, a tubular portion adapted to be passed through an opening in a sheet and to be bent to form a flange, and a portion projecting outwardly of the tubular portion and adapted to cooperate therewith to secure the element to the sheet, said tubular portion comprising a plurality of separate members each arranged to overlap the adjacent members at least in part and being in mutual bracing and reinforcing relation.

4. In a one-piece snap fastener element, an attaching portion comprising a plurality of separate members each arranged to overlap the adjacent member at least at the end portion thereof, and thereby to brace and reinforce each other against distortion, said members being arranged in tubular formation and adapted to be bent outwardly therefrom and out of their overlapping relation to form an annular flange.

5. In a one-piece snap fastener element, a tubular attaching portion adapted to be passed

through an opening in a sheet to which the element is to be secured, and adapted to be bent to form an attaching flange, said portion comprising a plurality of similar mutually self-reinforcing members arranged in edge overlapping relation at the otherwise free extremities thereof and thereby bracing each other to resist the distorting action of a tumbling or setting operation.

6. In a one-piece snap fastener element, a tubular attaching portion of more than a single thickness of material, said portion comprising a plurality of separate members arranged in overlapping relation to mutually brace each other against the distorting effects of tumbling and setting operation.

7. A one-piece fastener element provided with separate members terminating at their upper ends in an integral connecting portion and at their lower ends in a tubular portion, said members being arranged in overlapping relation to said tubular portion to provide more than one thickness of material therein and to brace each other against the member distorting tendencies of tumbling and setting operations.

8. A snap fastener element adapted to be attached to a sheet including an attaching portion comprising a plurality of separate members having the upper portions thereof arranged in the form of a tube and passing through an opening in the sheet and contacting with the wall of the opening, and having the lower portions thereof first arranged in edge overlapping relation and bent outwardly out of their overlapping relation on to a face of the sheet and thereby forming an annular attaching flange of a plurality of contacting segments, each of the members constituting one of the segments.

9. A snap fastener element for a sheet having an opening therein for the passage of part of the element comprising an attaching portion adapted to be passed through the opening in the sheet and bent on to a face of the sheet to form an annular flange to secure the element to the sheet, said attaching portion comprising a predetermined number of separate, self-bracing, overlapping members of greatest width at their peripheral edges and tapering to a narrower width, said width being substantially equal to the outermost circumference of the annular flange divided by said predetermined number.

10. The method of making a one-piece snap fastener element from a flat blank having a plurality of radiating arms comprising bending the central portion of the blank to form the head portion of the element, and bending the arms into mutually bracing overlapping relation and into the form of a tube to resist the distorting tendencies on said arms of subsequent tumbling and setting operations.

11. A one-piece socket provided with separate members terminating at their upper ends in an integral connecting portion, and at their lower ends in a tubular portion, the alternate members being bent out of the tubular portion to provide resilient fingers, and the remaining members being arranged in overlapping relation.

12. In a one-piece socket provided with a continuous cap portion, a tubular attaching portion comprising separate members extending from and integral with the cap portion, alternate members being arranged in overlapping relation to provide more than one thickness of material in said tubular portion, and the end parts of the remaining members projecting inwardly of the

tubular portion to form stud-engaging resilient fingers.

13. The method of making a one-piece snap fastener element from a flat blank having a plurality of radiating arms comprising drawing up the central portion of the blank into the head portion of the element, bending the arms into overlapping relation and into the form of a tube to carry the arms into mutually bracing relation and to resist the distorting tendencies of the

tumbling and setting steps hereinafter mentioned, tumbling the element, setting the element by passing the end portions of said arms through an opening in a sheet, and spreading said end portions outwardly from the overlapping position thereof into edge contact, each to form a segment of an annular attaching flange and together to form the substantially complete annular flange.

DANIEL I. REITER. 10
